(57) **CLAIM**

I claim the ornamental design for a cosmetic case, as shown and described.

DESCRIPTION

FIG. 1 is a top perspective view of the cosmetic case shown in a closed position;

FIG. 2 is a top view thereof;

FIG. 3 is a bottom view thereof;

FIG. 4 is a back view thereof;

FIG. 5 is a front view thereof;

FIG. 6 is a right side view thereof;

FIG. 7 is a left side view of the first embodiment of the cosmetic case shown in an assembled position;

FIG. 8 is a bottom perspective view thereof;

FIG. 9 is top perspective view thereof;

FIG. 10 is a top view thereof;

FIG. 11 is a bottom view thereof;

FIG. 12 is a front view thereof;

FIG. 13 is a back view thereof;

FIG. 14 is a right side view thereof;

FIG. 15 is a left side view thereof;

FIG. 16 is a bottom perspective view thereof;

FIG. 17 is a top perspective view of a second embodiment of the cosmetic case shown in an assembled position;

FIG. 18 is a top view thereof;

FIG. 19 is a bottom view thereof;

FIG. 20 is a front view thereof;

FIG. 21 is a back view thereof;

FIG. 22 is a right side view thereof;

FIG. 23 is a left side view thereof;

FIG. 24 is a top perspective view thereof, with the mirror rotated at a different angle when compared with the position of the mirror in FIG. 17; and,

FIG. 25 is a top perspective exploded view thereof.

The dashed lines in FIGS. 17-18 and 24-25 represent environmental structure and form no part of the claimed design.

All other surface(s) or portion(s) of the embodiments of my designs not shown in the figures or otherwise described in the specification form no part of the claimed designs.
